UNITED STATES PATENT OFFICE.

THOMAS J. McWILLIAMS, OF CLEVELAND, OHIO, ASSIGNOR TO HERMAN J. TRENKAMP,
OF CLEVELAND, OHIO.

STOVE-DOOR FITTING.

1,294,683.

Specification of Letters Patent. Patented Oct. 25, 1921.

Application filed February 24, 1920. Serial No. 361,037.

To all whom it may concern:

Be it known that I, THOMAS J. McWILLIAMS, a citizen of the United States, residing at 1519 Clark avenue, in the city of Cleveland, county of Cuyahoga, and State of Ohio, have invented a new and useful Improvement in Stove-Door Fittings, of which the following is a specification, the principle of the invention being herein explained and the best mode in which I have contemplated applying that principle, so as to distinguish it from other inventions.

My invention pertains to a stove door fitting and more particularly to the manner of connecting a stove door about its hinge.

The objects of my invention, besides designing a construction of this character which will be of simple, durable and sightly construction, are:—

1. To conceal a lug required to support a downwardly swinging door when it is in its lowermost or substantially horizontal position. Instead of having such lug, which is commonly used for this purpose, positioned in front and externally, I reverse the construction by providing the lug internally and behind the plane of the door opening. Instead of the door swinging down to rest upon the lug or lugs a projection from the bottom of the door swings upwardly against the underside of a lug or lugs.

2. To provide flush bordering surfaces for the sill of a peculiar "door in a door" construction shown described and claimed in the co-pending H. J. Trenkamp application for "Stove oven entry" filed May 9, 1919, Serial No. 295,885. According to the disclosure of such prior application a large door was hung to swing downwardly and such large door carried two complementary doors hinged to swing in opposite directions sidewise. My present invention enables dishes to be slid out of the oven compartment without encountering a ridge where the edge of the door conforms to the edge of the oven compartment; and this facility obtains regardless of which door is open.

Adverting to the drawings:—

Figure I is a front elevation of a stove embodying my invention, showing all doors closed.

Fig. II is a horizontal section on line II—II of Fig. I looking downwardly.

Fig. III is a vertical section on line

III—III of Fig. I looking to the left, and 55 with the main door open.

Fig. IV is an enlarged vertical section on line IV—IV of Fig. I looking toward a hinge showing the relation of the parts when the door is closed. 60

Fig. V is a section corresponding to that of Fig. IV showing the relation of the parts when the door is opened.

Fig. VI is an enlarged fragmentary front elevation with certain portions indicated in 65 dotted lines.

Fig. VII is a section on line VII—VII of Fig. VI.

Fig. VIII is a similarly enlarged horizontal section on line VIII—VIII of Fig. I. 70

The stove casing is supported on four legs 1 and comprises a bottom 2, a front frame 3, side walls 4, a rear wall 5 having an opening above in communication with a stack 6 and a top 7. Supported in any suitable 75 manner within the stove casing so as to be spaced from the side walls 4 and the rear wall 5 is an oven compartment comprising a bottom 8, rear wall 9 and side walls 10. Inasmuch as the manner of so supporting 80 an oven is old in the art and forms no part of this invention its detailed description has been dispensed with. In consequence however, of such spaced relation of the oven compartment, an enveloping flue space 11 is 85 provided. Carried by the inner surface of the rear wall 5 are brackets 12 supporting each one end of burners 13 which have their opposite ends 14 supported in the front wall 3. The manner of igniting the burners 13 90 is of no interest to this application. Suffice it to say that each burner 13 is located underneath the middle of one lateral half of the oven compartment. The burners 13 are both supplied with fuel from a gas supply 95 pipe 15, from which the flow is controlled by valves 16.

It is to be understood that the entire space available within the stove for the purposes of an oven is open at the front side 100 but may be divided in half by means of a removable partition 17 shown in Figs. II and III. A large door will afford access to the entire oven space while two smaller doors will afford access to the divisions of 105 the oven on opposite sides of the partition 17 when the latter is in place.

As will be observed in Fig. VIII the edge 18

of the stove frame which borders the oven compartment is slightly recessed. This has a co-operative purpose which will be herein-after explained. The large door 19 is provided with a handle 20 and is supported at its lower edge by means of a pair of trunnions 21, being thus adapted to swing downwardly toward a horizontal position. Means is provided for limiting such downward 5 swinging movement and the arrangement is additionally such that when the horizontal position is reached no part of the door will project higher than the level of the bottom 8. Secured to the trunnions 21 are a pair of 10 levers 22 and connected with the free ends of the latter are a pair of tension springs 23. The opposite ends of these springs are attached to the frame of the stove in a manner not shown, but the connection is adapted 15 to resist the downward swing of the door 19 and to ease its return or closing action. The two extreme positions of the lever 22 and spring 23 are shown in Figs. V and VII respectively. The front frame of the stove 20 is provided on opposite sides with a pair of forwardly curved caps 24 adapted to inclose the trunnions 21 and conceal the levers 22. Depending from the two lower corners of the door 19 are a pair of lugs 25 adapted 25 to swing upwardly to the rear in suitable recesses 26 as shown in Figs. I and IV to VII inclusive, so as eventually to engage abutments or stop surfaces 27 as shown in Fig. V. When such engagement occurs the 30 main door 19 will be in a substantially horizontal position, according to one feature of my invention. The inside surface 28 of that portion of the door frame which extends between the trunnions 21 will be precisely 35 level with the upper surface of the bottom 8 of the oven compartment as appears in Fig. III and still more clearly in Fig. V. This makes it very much easier to withdraw any baking receptacle and enables the same 40 to be slid smoothly owing to the absence of any obstructing edges.

As may be seen in Fig. VIII the innermost upright edge 29 of the main door frame 19 is adapted to abut the recessed edge 18 when 45 the main door is closed thereby affording an effectual heat seal.

Hinged at 30 and 31 on two opposite sides of the main door are a pair of smaller doors 32 and 33 provided with handles 34 and 25 respectively. These doors are adapted to swing laterally in opposite directions when the main door is closed. Inspection again 55 of Fig. VIII discloses that when the door 32 is closed against the frame 19, it effects 60 engagement therewith along an upwardly extending plane 36 thereby similarly forming a heat seal.

For the same reason that the surface 28 is level with the bottom 8 when the main 65 door is open, I have so designed the con-

struction that the innermost surfaces of the smaller doors will then also assume a substantially horizontal position likewise level with both of the surfaces 27 and 28. The inner surface 37 of the door 32 is clearly 70 shown in Fig. V.

Clearly, it is of equal advantage to be able to withdraw a baking dish without having its bottom encounter an obstruction when either of the smaller doors 32 or 33 are open. 75 I have, therefore, as appears in Fig. IV, also so fitted the parts that the upper edge 38 of the main door frame 19 which borders the lower horizontal front line of the oven compartment will, when the main door is 80 closed rest level with the bottom 8. In this manner, when either of the smaller doors is open, a baking receptacle may be withdrawn smoothly or momentarily allowed to rest in a level position partly upon the bottom 8 85 and partly upon such bordering edge 38 preparatory to being regripped and either returned for further baking or lifted out of the oven. Since the upper edge 38 moves only when the large door opens, manifestly, 90 it occupies the same position as shown in Fig. IV when the smaller door 32 is open. Therefore, if the door 32 is considered as having been swung open and out of the way, it is clear that baking utensils may be 95 smoothly slid from the bottom 8 over the surface 38 which remains level therewith.

I claim:—

1. A stove door fitting comprising the combination with a stove having an oven 100 compartment, of a door adapted to afford access to one entire side of said compartment and to have its inside wall rest level with the bottom of said compartment, another door carried by said first mentioned 105 door and adapted to afford direct access to only a part of said compartment, a stationary part of said larger door resting level with the bottom of said oven compartment to form a continuous smooth surface when 110 said smaller door is opened.

2. A stove door fitting comprising the combination with a stove having an oven compartment, provided with a sill, of a horizontally hinged door adapted to afford access to one entire side of said compartment and to have its inside wall rest level with said sill, another door vertically hinged to said first mentioned door and adapted to afford direct access to only a part of said 115 compartment, the arrangement being such the lower horizontal sill of said larger door rests level with the bottom of said oven compartment to form a continuous smooth surface when said smaller door is opened. 120

3. A stove door fitting comprising in combination, a compartment provided with a recess in front and a door provided with a lug adapted to engage the top of said recess. 125

4. A device of the character described 130

- comprising a support provided with a substantially horizontal surface, and a member movably attached to said support, said member being fashioned with two surfaces angularly disposed with reference to each other, each of said member surfaces being adapted to assume a position level with said support surface depending upon the position of said member relative to said support.
- 5 10 5. A stove door fitting comprising the combination with a stove having an oven compartment including a bottom, of a door for said oven and movably carried by said stove, said door being adapted to assume two different positions of rest and fashioned with surfaces adjacent to a defining edge of said oven compartment and adapted each to come level with said bottom when said door is in one of its positions of rest.
- 15 20 6. A stove door fitting comprising the combination with a stove having an oven compartment including a bottom, of a main door for said oven and hinged to said stove, a smaller door hinged to said main door, the latter being fashioned with edges bordering an edge of said oven compartment and each adapted to assume a position substantially level with said oven bottom when the main door is open and closed respectively, where-
- by baking utensils may be smoothly slid from said oven regardless of which door is opened.
7. A stove door fitting comprising the combination with an oven bottom, of a door provided with distinct edges adapted to lie level with said bottom when said door is open and closed respectively.
8. A stove door fitting comprising the combination with an oven bottom, of a pair of doors to said oven carried one by the other, said carrying door provided with distinct edge surfaces disposed in angularly related planes, one of said edges being level with said oven bottom when such carrying door is open, and the other edge surface being level with said oven bottom when such carrying door is closed for the purpose specified.
9. A stove door fitting comprising in combination, a compartment provided with an abutment, a spring attached to said compartment and a door provided with two lugs, one lug adapted to engage said abutment and the other lug to be restrained by said spring respectively. 55

Signed by me, this 21st day of January, 1920.

THOMAS J. McWILLIAMS.
